CRUTCH HAND GRIP

Ernest Schmid and Rainer Schmid, both of
2006 S. 13th St., Broadview, Ill. 60153

Filed Aug. 22, 1966, Ser. No. 3,552

Term of patent 14 years

(Cl. D83—1)

FIG. 1 is a top plan view of a crutch hand grip, embodying our new design;

FIG. 2 is a side elevation thereof;

FIG. 3 is an elevation as seen from the opposite side of FIG. 2;

FIG. 4 is an end elevation as seen from the right of FIG. 1;

FIG. 5 is an end elevation as seen from the left of FIG. 1;

FIG. 6 is a bottom plan view thereof;

FIG. 7 is a cross-section taken on line 7-7 of FIG. 1;

FIG. 8 is a cross-section taken on line 8-8 of FIG. 1;

FIG. 9 is a cross-section taken on line 9-9 of FIG. 1.

We claim:

The ornamental design for a crutch hand grip, substantially as shown.
